UNITED STATES PATENT OFFICE.

JAMES K. P. PINE, OF LANSINGBURG, AND ISAAC P. TURNER AND WILLARD W. SEARLE, OF TROY, NEW YORK.

MANUFACTURE OF COLLARS.

SPECIFICATION forming part of Letters Patent No. 269,229, dated December 19, 1882.

Application filed March 6, 1882. (Model.)

To all whom it may concern:

Be it known that we, JAMES K. P. PINE, a resident of the village of Lansingburg, county of Rensselaer, State of New York, and ISAAC P. 5 TURNER and WILLARD W. SEARLE, residents of the city of Troy, State and county aforesaid, have invented a new and useful Method for Turning and Securing the Edges of Collar-Band Blanks, of which the following is a specification.

Our invention relates to certain improvements in the manner of uniting and turning the edges of collar-band blanks; and it consists in first producing upon the outer cut edge 15 of one of the blanks, or upon the outer cut edges of two of the blanks when three thicknesses of material are used to produce a band, and before the band-blanks are sewed to the collar on their inner edges, folded over and 20 turned down to close, a sewed and turned or hemmed edge, so that when the other and inner edges of the band-blanks are sewed to the collar and the band-blanks are turned over and folded down preparatory to closing them, 25 the blank or blanks having the sewed and turned or hemmed outer edge will serve as a guide for turning in the outer edge of the other blank, so as to secure parallel coincidence and a uniformity of width.

30 In the accompanying drawings, forming a part of this specification, there are six figures illustrating our invention, and in all of which the same designation of parts by letter-reference is used, and all the vertical sectional 35 illustrations of the parts are exaggerated in width and thickness to show them.

Figure 1 illustrates in a vertical section two band-blanks, O' O'', having a row of stitching, S', near their outer edges, preparatory to turning and creasing them when sewed, with the inner edges of the blanks designated at a, this being one method of forming a guide-edge when the band is made of three or more blanks. Fig. 2 illustrates in a vertical section two band-blanks, O' O'', having their combined outer edges felled down by the stitching S'', to form a guide-edge, b, when three or more thicknesses are used to make the band, the inner edges of the blanks which attach to the collar-bottom being designated at a. Fig. 3 shows in a vertical section the position of the sewed

blanks illustrated in Fig. 1 after they have been turned so as to form the outer guide-edge, b. Fig. 4 represents in vertical section the collar and attached band after the blanks composing the latter upon their inner edges (designated at a a) have been laid parallel with the edge of the collar-bottom, and the latter intermediately placed and the parts stitched at S''', with the two sides of the band turned over the latter stitching and folded, with the outer edge of the band-blank O''' turned in so as to coincide with the guide-edge b, and the band closed by the stitching S⁴; the position of the band-blank O''' (which forms one facing of the band) 65 before being turned in on its outer edge, so as to coincide with the guide-edge b, being shown by a dotted line, the guide-edge shown in this figure being that illustrated in Fig. 2. Fig. 5 illustrates in vertical section that which is 70 shown in Fig. 4, with the exception that the guide-edge b is formed as shown in Figs. 1 and 3, and represents a vertical section taken on the line x x of Fig. 6, with the width and thickness of the parts exaggerated, as before stated. 75 Fig. 6 represents a plan view of one side of the collar.

As the outer edges of collar-band blanks which form the band are usually turned in to close them after they have been attached to 80 the collar-bottom, it requires skilled labor and an educated eye to obtain uniformity of band width, even from the same widths of band-blanks, and often where the greatest care is exercised this irregularity will occur at times 85 and prominently will appear when the goods have been laundered and are being bunched to package them. Where collar-band blanks are made of such width that when folded longitudinally the inner fold will form a thickness 90 of the ply, as has been done before, the outer folded edge of the double band-blank does not produce a secured and finished guide-edge, but one that requires subsequent creasing and adjustment with the use of skilled labor to hold it in position while the other band-blanks are being turned in to coincide with it. 95 Another difficulty occurs where this latter method of using a folded blank-edge is employed, in the fact that it can only be applied to such collars as have bands which are straight upon their bottom edge, while our differing 100

method of producing a guide-edge upon the cut lower edges of the blanks any form of curve can be applied to the bottom of the bands. To avoid this difficulty we produce the guide-edge *b* upon the outer edge of the blanks or blank forming one facing of the band before the band-blanks are attached on their inner edges to the bottom of the collar-body, and at a stage in the production of the collar when it can be done with accuracy and uniformity. After this has been done and the blanks forming the two facings of the band are laid for stitching, with their inner edges parallel to the bottom of the collar-body, and the latter between the band-facings, with that one of the latter having the guide-edge on top, the stitching which unites the parts, as designated at *S'''*, by means of a gage, can be located with reference to the guide-edge so as to secure a uniform width of band in each instance. This being accomplished, after the facings of the band are turned over and folded to close, that facing having a guide-edge and fixed width furnishes a measure to turn in the edge of the other facing, so as to secure uniformity, when the edges are sewed by means of the stitching *S⁴*. To thus attach and secure the bands but little skill is required to secure absolute uniformity, and any kind of guide-edge will answer the purpose which will, when closed in, produce a good finish.

The collars made according to this method are uniform in the band width and the work

is done just as well by children as any one else, while under the old process skilled labor is required, and even the best of the latter class are unable to produce a uniform product. The facility and accuracy with which the work can be done adds greatly to the value of the process.

Having thus described our invention, what we claim, and desire to secure by Letters Patent, is—

The method herein described of attaching collar-bands to collars, consisting in forming upon the outer cut edge of one of the blanks, or on the outer cut edges of two of them when three or more are employed, a sewed and turned or hemmed edge, so that when the inner edges of the band-blanks are laid parallel to the lower edge of the collar-body, which is placed intermediate, and the parts are thus sewed, and then turning over and down the blanks to close the bottom, the blank or blanks having the sewed and turned or hemmed edge serving as a guide for turning in and sewing the other parts of the band.

Signed at Troy, New York, this 28th day of February, 1882.

JAS. K. P. PINE.
ISAAC P. TURNER.
WILLARD W. SEARLE.
